UNITED STATES PATENT OFFICE.

GROVER CHRISTERN, OF NEW YORK, N. Y.

SPARK-PLUG.

1,400,525.

Specification of Letters Patent. Patented Dec. 20, 1921.

Application filed November 17, 1919, Serial No. 338,607. Renewed June 7, 1921. Serial No. 475,831.

To all whom it may concern:

Be it known that I, GROVER CHRISTERN, a citizen of the United States, and a resident of the city of New York, county of Bronx, and State of New York, have invented a certain new and useful Improvement in Spark-Plugs, of which the following is a specification.

This invention relates to an improvement 10 in spark plugs of the type generally used in internal combustion engines. One of the objects of this invention is to provide an article of this character having adjustable or regulatable electrodes by means of 15 which the space between said electrodes or points may be readily adjusted or altered to compensate for wear or when desired, the points may be readily engaged or separated to such an extent as to conveniently 20 permit the removal of any carbon or oil deposit which may lodge between the points, and thereby incidentally removing any ex- 25 crescence which may become settled in the electrode.

These objects, and other objects which hereinafter appear in view, I have devised 30 the particular arrangement of all parts hereinafter set forth and more particularly pointed out in the claims appended hereto.

Reference is to be had to the accompanying drawings, forming a part hereof, in which—

Figure 1 is a vertical sectional elevation of a spark plug provided with my improvement.

Fig. 2 is a side elevation of the same.

Fig. 3 is a plan view of the same, and

Fig. 4 is a sectional view of the lower end of the plug showing the manner in 40 which the points engage and are cleaned by contact with one another.

Throughout the various views of the drawing, similar reference characters designate similar parts.

In the preferred embodiment of my invention, as illustrated in the accompanying drawing, 1 indicates the usual metal body of the plug which may be of the usual or desired form and which is provided with 45 the conventional screw threads 2 by means of which the same is threaded into the spark plug opening in an engine cylinder. At the lower end of the spark plug body is a cross member 3 which forms one of the 50 electrodes and which is provided with a central conical opening 4. Mounted in the body 55 of the plug is the insulating material 5 which is usually of mica, porcelain or the like. Extending vertically through the center of the insulating material 5 is a tubular member 6. This tubular member is threaded, as at 7, on its upper end and on its lower end it is provided with a circumferential flange 8 which fits snugly into the flared mouth 9 of the insulator 5 at its lower end. 60 The tubular member 6 is held tightly in place within the insulator 5 by the co-operation of the flange 8 on its lower end and a washer 10 and a nut 11 threaded upon the screw threads 7 on its upper end. The 65 washer 10 and nut 11 are covered by a cap 12 which passes over the upper end of the tubular body 6 and rests upon a shoulder 13 on the insulator 5. Threaded upon the upper end of the tubular member 6 is a 70 bushing 14 provided with a base 15 and an inwardly extending projection 16 on its upper edge. Slidably mounted within said bushing 14 is a disk 17 having an upwardly extending conical projection 18 which is 75 provided with a slot 19 for engagement by a screw driver or other implement, whereby the disk 17 may be rotated within the bushing 14. Attached to the disk 17 and extending downwardly therefrom, is the central 80 electrode or spark plug point 20 which is in the nature of a rod and which passes through the tubular member 6. At its lower end this electrode 20 is provided with the plug point 21 which is preferably dia- 85 mond shaped, as shown, or may be of any desired or suitable contour. A spring 22 is mounted within the bushing 14 and tends to exert an upward pressure upon the under face of the disk 17. Said disk 17 is limited 90 or restricted in its upward movement by reason of the engagement of the projection 16 on the bushing 14 with the upper face of the disk 17. This disk 17 is provided with a number of recesses 23. I have shown 95 three of these recesses in the drawing, but it is obvious that this number may be varied according to requirements. It will be seen that when the projection 16 registers with one of these recesses 23 it will fit thereinto, 100 and the point 21 on the central electrode 20 will be nearer or farther away from the electrode 3 according to the depth of the recess 23 in which the projection 16 fits. These recesses 23 are therefore made of varying 105 depths so that the distance between the points is regulated by the depth of the par-

ticular recess into which the projection 16 fits. To regulate the distance between the points of the plug, a screw driver is inserted into the slot 19 and the disk 17 is pressed 5 downwardly until the projection 16 moves out of engagement with the slot into which it is resting. Then the disk 17 is rotated until the projection 16 comes into registration with the recess of desired depth when 10 pressure on the screw driver is released and the spring 22 forces the recess 23 into engagement with the projection 16.

In Fig. 4 is shown the manner in which the points of the plugs are cleaned. When 15 the conical opening 4 in the electrode 3 becomes clogged or corroded, the electrode 20 is pressed downwardly until its diamond shaped point 21 enters the conical opening 4. By then rotating the electrode 20 the 20 opening 21 is cleaned by the point 21 as disclosed in Fig. 4.

From the foregoing it is obvious that my 25 invention is not to be restricted to the exact embodiment shown, but is broad enough to cover all structures coming within the scope of the annexed claims.

Having described my invention what I claim is:

1. An article of the class described com-

prising a spark plug having a fixed electrode, a movable electrode having an end adapted to be brought into contact with the fixed electrode and rotated while in contact therewith to clean the same, a disk fixed to the upper end of said electrode having a plurality of recesses of varying depths, and a projection on the plug adapted to be brought to rest in any one of said recesses by rotation of the movable electrode. 30

2. An article of the class described comprising a spark plug having a fixed electrode, a movable electrode vertically movable through the plug and adapted to be brought into contact with the fixed electrode and rotated while in contact therewith to clean 45 the same, a disk fixed to the upper end of said electrode and rotatable with the same, a bushing in which said disk is rotatable, said disk having a plurality of recesses of varying depths and an inwardly extending 50 projection on said bushing adapted to be brought to rest in any one of said recesses by rotation of the movable electrode. 40

Signed at the city of New York, county of and State of New York, this 11th day of 55 November, 1919.

GROVER CHRISTERN.
